UNITED STATES PATENT OFFICE.

WILLIAM L. AFFELDER AND MARK GORTON, OF BROWNFIELD, PENNSYLVANIA.

APPARATUS FOR WATERING COKE IN COKE-OVENs.

954,241.

Specification of Letters Patent.

Patented Apr. 5, 1910.

Application filed January 18, 1910. Serial No. 538,724.

To all whom it may concern:

Be it known that we, WILLIAM L. AFFELDER and MARK GORTON, of Brownfield, Fayette county, and State of Pennsylvania, have invented a new and useful Improvement in Apparatus for Watering Coke in Coke-Ovens, of which the following is a full, clear, and exact description, reference being had to the accompanying drawings, forming part of this specification, in which—

Figure 1 is a side elevation of apparatus embodying our invention and showing the same in connection with a coke oven, the sprinkling heads being shown as extending into the oven in watering position. Fig. 2 is a side elevation of the apparatus on a larger scale and looking at it from the opposite side from Fig. 1. Fig. 3 is a detail view showing the slide mounting of the watering apparatus on the truck. Fig. 4 is an end view partly in section, the section being on the line IV—IV of Fig. 1. Fig. 5 is a top plan view; and Fig. 6 is a detail view showing the automatic cut off.

Our invention has relation to apparatus for water quenching coke in coke ovens, more particularly rectangular ovens, and is an improvement upon the apparatus for this purpose which is described and claimed in our Patent No. 949,290, dated Feb. 15, 1910. In that application we have described and claimed apparatus of this character comprising a hydraulic motor having its piston provided with a sprinkling head designed to be reciprocated within the coke oven, together with means whereby the water which actuates the motor is subsequently discharged by the sprinkler head and used for quenching the coke.

Our present invention, while retaining this feature, is designed to increase the rapidity of the quenching operation by providing additional sprinkling means which operate in conjunction with the first named means.

A further object of our invention is to provide an improved mounting for the apparatus whereby a full stroke of the sprinkler heads may be obtained within the oven and which, after the quenching operation has been completed in any one oven, will permit the apparatus to be withdrawn a sufficient distance to clear the oven doors in moving it to an adjacent oven.

A still further object is to provide means

for automatically stopping the operation of the motor when the quenching operation has been completed in any oven.

The precise nature of our invention will be best understood by reference to the accompanying drawings, which will now be described, it being premised, however, that various changes may be made in the details of construction, form, and arrangement of the various parts without departing from the spirit and scope of our invention as defined in the appended claims.

In these drawings the numeral 2 designates a coke oven of the rectangular type. In practice there is a series of these ovens placed side by side, and extending along each side of the series are parallel tracks; one of these tracks is shown at 3. Mounted upon each track is a carriage or truck 4 of any suitable construction and which may be propelled along the track to move the apparatus from one oven to another by any suitable motive power. In the drawing we have shown a crank operated propelling mechanism 6. The watering apparatus comprising our invention is mounted upon this truck or carriage; and it will be understood from the foregoing that in practice a similar apparatus is provided at each side of the series of ovens, the sprinkling heads being arranged to enter doors at the respective sides of the ovens and to be reciprocated over one-half of the area of the coke beds therein. It will be understood, however, that if desired, the apparatus may be used at one side only of the oven and the sprinkler heads may be arranged to be reciprocated entirely across the oven.

Inasmuch as the watering apparatus at one side of the series of ovens is a duplicate of that at the opposite side, we have shown and will describe but one apparatus. This apparatus comprises a cylinder 7 having therein a reciprocating piston carried by a hollow piston rod 8 which extends outwardly through a stuffing box 9 at one end of the cylinder. Connected to the projecting end of this hollow rod is a sprinkler head 10 extending transversely of the rod and provided with a plurality of discharge perforations 11, and terminating in backwardly directed end portions 12, also provided with discharge perforations. The motor cylinder is provided with a valve shifting motor or engine 13 of the general character described in our said patent. The piston is also pro-

vided with valve means for admitting water from the exhaust side of the piston into the hollow piston rod to be thence discharged by the sprinkler head 10, such valve means being also preferably similar to that described in our said patent and having similar actuating connections 14, 15, 16, 17, 18 and 19. The motor which we have herein shown, is, in fact, of the same general type and mode of operation as that described in our said patent and need not be described herein in detail.

20 designates a water supply pipe supported on the truck or carriage 4 and having a supply connection 21. The pipe 20 is connected with the pipe 25 by the pipe 24, and is also connected with the front end portion of the cylinder by the pipe 24^a. The connection 24^a is for the purpose of filling the front end of the cylinder in starting the apparatus, and is provided with a hand valve 24^b which is closed as soon as the filling is completed and remains closed during the operation of the apparatus. The valve chamber 23 is connected to the rear valve chamber 22 by the longitudinal pipe 25 through which water is supplied to the two ends of the motor during the operation of the apparatus.

30 The hollow piston rod and sprinkler head 10 are guided and supported in their reciprocating movements by means of the two parallel pipes 27 and 28 which are of a length greater than the length of the motor cylinder and are arranged above said cylinder and parallel therewith. These pipes 27 and 28, which are arranged to reciprocate with the hollow piston rod, are mounted on suitable guides, preferably roller guides, such as indicated at 29, carried by suitable brackets 30 connected to the motor cylinder. The two pipes are further supported and made rigid with respect to each other by means of the interposed brackets 31. The 40 two pipes 27 and 28 are connected at both ends by means of the fittings or couplings 32 and 33. The fitting or coupling 32 is connected at one end to the water supply pipe 20 by means of a flexible hose 34. The forward ends of the two pipes 27 and 28 are also connected with each other and with the piston rod 8 by a rigid connection 35; and the fitting 33 has connected thereto a sprinkler head 36 which is located in front of and parallel with the sprinkler head 10, this head being similar to the head 10.

37 wherever seen designates a hand valve in the water supply connections.

38 designates drain cocks for the valve chambers 22 and 23.

39 designates a valve placed in the pipe 20 and arranged to control the admission of water to the pipe 25 and also to the pipes 27 and 28.

65 In the operation of the apparatus, the

sprinkler heads 10 and 36 are reciprocated within the oven a sufficient and predetermined number of times to complete the quenching operation; and when this operation has been completed, it is desirable to provide automatic means for closing the valve 39 so as to stop the motor with the sprinkler heads in their retracted positions. For this purpose we provide the longitudinal reciprocating rod 40 which is slidably supported in a suitable bearing 41 attached to the motor cylinder and which is provided at its forward end with a suitable projection 42 adapted to be engaged with the connecting member 35 at the end of each backward stroke of the sprinkler heads. This rod is provided with a returning spring 42^a which returns it to its normal position after each operation. Connected to the rod 40 is a pawl 43 which is arranged to engage the teeth of a ratchet wheel 44 mounted upon one side of the motor cylinder, as best shown in Fig. 6. Loosely mounted on the shaft 45 of this wheel 44 is a lever arm 46 which is connected by a link 47 with an arm 48 on the stem of the valve 39. The wheel 44 is provided with a plurality of pin-holes 49 arranged in a circular series, a pin 50 being provided to be inserted in any one of these holes according to the number of reciprocations which it is desired to give the sprinkler heads 10 and 36 in each oven before the motor is automatically stopped.

In operation, the rod 40 will be actuated at the completion of each return stroke of the sprinkler heads and through the pawl 43, will move the wheel 44 one tooth for each complete reciprocation of the sprinkler heads. When the wheel 44 has been moved a sufficient distance to cause the pin 50 to engage with the lever 46, the valve 39 is automatically closed. This stops the motor with the sprinkler heads in their retracted position and after they have made a complete return stroke. By shifting the position of the pin 50 it will be obvious that this stop of the motor may be made to occur after any desired number of reciprocations within the limit of control of the wheel 44.

115 After the quenching operation has been completed in one oven, it is necessary to retract the sprinkler heads a sufficient distance to clear the oven doors and allow the apparatus to be moved along the series of ovens to another oven. This might be accomplished by causing the sprinkler heads to move entirely clear of the oven at the end of each return stroke. This, however, would result in loss of water during the time the sprinkler heads were outside the oven on each stroke. To avoid this loss of water and at the same time accomplish the desired result above stated, we mount the motor cylinder in a shoe or saddle 51 (best

shown in Fig. 3) and which is slidably mounted upon suitable guides 52 on the truck 4. The shoe or saddle is provided with a rack bar 53, whose teeth are engaged by a pinion 54 on a transverse shaft 55 also mounted on the truck 4 and having an operating crank 56 at one end. By means of this sliding shoe or saddle, and the operating means therefor, it will be readily seen that after the completion of a quenching operation, the slide can be operated to retract the sprinkler heads sufficiently to clear the oven in being moved to another oven.

15 The operation of the apparatus will be readily understood from the foregoing description. At each reciprocation of the sprinkler heads water will be discharged across the entire width of the oven from each sprinkler head, the sprinkler head 10 receiving its supply of water from the exhaust of the motor cylinder in the manner described in our said patent; while the head 36 receives its supply directly from the pipe 25 20, and this water being made to pass through the pipes 27 and 28 on its way to the head 36. By providing these two sprinkler heads, we not only retain the advantages of the apparatus of our previous patent in utilizing the exhaust water from the motor; but we largely increase the rapidity of the quenching operation. By passing the water for the head 36 through the pipes 27 and 28, these pipes are kept cool while in the oven.

30 35 After the sprinkler heads have made the required number of reciprocations in any particular oven, the valve 39 is automatically closed in the manner before described and the motor is stopped with the heads in their 40 retracted position. The crank 56 is then operated to move the apparatus back a sufficient distance to cause the heads to clear the oven. The truck 4 is then moved along the track 3 to another oven; the shaft 55 is then 45 operated to move the apparatus toward that oven; and the valve 39 is then manually opened to again start the motor. In order to provide for the forward and back movement of the apparatus on the truck 4 by the 50 operation of the shoe or saddle 51 without interference with the valve 39, the link 47 is provided with a lost motion connection, such as indicated at 47^a in Fig. 6, with the lever 48 of the valve stem.

55 It will be obvious that many changes may be made in the details of construction and form and arrangement of the several parts of the apparatus. Thus, we may employ any suitable form of carriage or truck upon 60 which the apparatus is mounted, this carriage or truck may be provided with any suitable means for moving it along the track 3; the apparatus may be mounted in various ways upon the carriage or truck to obtain 65 the forward and back movement herein de-

scribed; the automatic cut off valve for the motor may be variously arranged and actuated in different ways; the sprinkler heads may be of any desired form, other forms of motors may be employed, and various other changes may be made.

What we claim is:

1. In apparatus of the character described, a motor, a sprinkling device arranged to be reciprocated by the motor and to utilize the exhaust water from the motor, and a second sprinkling device having another source of supply and also arranged to be reciprocated by the motor; substantially as described. 75
2. In apparatus of the character described, a motor, a sprinkler head arranged to be reciprocated by the motor and to utilize the exhaust water from the motor, a guiding and supporting device for the sprinkler head, another sprinkler head carried by the guiding and supporting device, and means whereby said device and its sprinkler head are also reciprocated by the motor; substantially as described. 80
3. In apparatus of the character described, a motor, a sprinkling head arranged to be reciprocated by the motor and to utilize the exhaust water therefrom, a longitudinal pipe forming a guide and support for the sprinkler head and arranged to be reciprocated therewith, a second sprinkler head carried by said pipe, and a source of water supply connected to said pipe and supplying the last named head; substantially as described. 90
4. In apparatus of the character described, a motor, a sprinkler head arranged to be reciprocated by the motor and to utilize the exhaust water from the motor, a second sprinkler head also reciprocated by the motor, and means for supplying water to the last named head; substantially as described. 100
5. In apparatus of the character described, a motor, and two sprinkler heads connected to said motor and arranged to be reciprocated thereby, one of said heads being located in advance of the other; substantially as described. 110
6. In apparatus of the character described, a motor, two sprinkler heads arranged to be reciprocated by the motor, and separate supply connections for said heads; substantially as described. 115
7. In apparatus of the character described, a motor, a sprinkler head arranged to be reciprocated by the motor and to utilize the exhaust water from the motor, a pair of guiding and supporting pipes carried by the motor and arranged to form a guide and support for the sprinkler head, another sprinkler head connected to said pipes, and means for supplying water to said pipes and thence to the last named sprinkler head; substantially as described. 125
8. In apparatus of the character described, a supporting carriage or truck, a 130

motor mounted thereon, a sprinkling head arranged to be reciprocated by the motor, and means for moving the sprinkling head longitudinally of the truck independently of the motor; substantially as described.

9. In apparatus of the character described, a carriage or truck, a motor mounted thereon, sprinkling apparatus actuated by the motor, and means whereby the motor and sprinkling apparatus may be moved longitudinally of the truck; substantially as described.

10. In apparatus of the character described, a carriage or truck, a support slidably mounted on the carriage or truck, and sprinkler apparatus mounted on said support; substantially as described.

11. In apparatus of the character described, a sprinkler head, a motor for reciprocating the head, a valve for controlling the supply of actuating fluid to the motor, and means operated by the movement of

the head for automatically cutting off the supply of water to the motor after a predetermined number of movements of the head; substantially as described.

12. In apparatus of the character described, a reciprocating motor, sprinkling apparatus actuated thereby, a valve controlling the supply of actuating fluid to the motor, and means actuated by the sprinkler head at the limit of its movement in one direction to automatically close said valve after a predetermined number of movements of the sprinkler head; substantially as described.

In testimony whereof, we have hereunto set our hands.

WILLIAM L. AFFELDER.
MARK GORTON.
